FIG. 1

FIG. 6

FIG. 7

FIG. 8

FIG. 9

FIG. 10

FIG. 11

FIG. 1 is a perspective view of a bread dough rounder bar, showing my new design;

FIG. 2 is a side view of the bread dough rounder bar of my new design;

FIG. 3 is a bottom view thereof;

FIG. 4 is a side view thereof opposite from the side shown in FIG. 2 and upside down;

FIG. 5 is a top view thereof;

FIGS. 6, 7, 8, 9, 10 and 11 are cross-sectional views thereof taken along the lines as shown in FIG. 2.

The dominant feature of the present invention resides in the specific configuration of the contact face of the rounder bar as best shown in FIGS. 2 and 3 and in cross-section in FIGS. 6-11.

I claim:

The ornamental design for a bread dough rounder bar, as shown and described.
